Oscar Roelke.

UNITED STATES PATENT OFFICE.

OSCAR ROELKE, OF ST. LOUIS, MISSOURI.

BOTTLE-TOP.

1,133,505.

Specification of Letters Patent.

Patented Mar. 30, 1915.

Application filed February 2, 1914. Serial No. 816,026.

To all whom it may concern:

Be it known that I, OSCAR ROELKE, a citizen of the United States, residing in the city of St. Louis and State of Missouri, have 5 invented certain new and useful Improvements in Bottle-Tops; and I do declare the following to be a full, clear, and exact description of the invention, such as will enable others skilled in the art to which it 10 appertains to make and use the same.

This invention relates to improvements in bottle tops and more particularly to those which are removably engaged with the necks of beer bottles or the like.

15 The object of the invention is to provide a bottle top of this character which may be very simply and cheaply constructed and which will form an effective closure for the top of a bottle when in position or may 20 readily be removed by hand.

With the above and minor objects in view, the invention resides in details of construction herein described and claimed and shown in the drawings wherein:

25 Figure 1 is a side elevation of a bottle showing my improved top applied thereto; Fig. 2 is a vertical section through the neck of a bottle and the top thereon; Fig. 3 is a horizontal section on the line 3—3 of Fig. 2; 30 Fig. 4 is a similar view of a cap alone when removed from the bottle; and Fig. 5 is a plan view of the resilient retaining element of the top.

In the accompanying drawings, the numeral 1 designates a bottle of ordinary construction provided with the usual external bead 2 around the upper end of its neck. The bottle forms no part of the present invention but closely coacts therewith.

40 Referring now, more particularly to details, my improved bottle top comprises an inverted cup-shaped, packing-receiving socket 3 the depending wall 4 of which is extended laterally as at 5, bent substantially 45 upon itself as at 6, and is then extended inwardly to form an annular flange 7.

A single piece of resilient wire 8 is bent at suitable points throughout its length as at 9 to form a polygonal retaining element. 50 The bends or corners 9 of this element are inserted within the space between the portions 5 and 7, which form a substantially U-shaped bead. When in this position, it will be seen that the individual resilient 55 arms 10 of said member are disposed in

position to snap over the bead 2 on the bottle 1, when the top is applied. I preferably provide a packing disk 11 loosely seated within the socket 3 of the top, said packing disk being compressed when the resilient 60 spring arms 10 engage the tapered underside of the bead 2.

By reference to the drawings, it will be seen that the resilient arms 10, when in their proper position, are so disposed in regard to 65 the packing disk 11, that they prevent said packing disk from becoming disengaged from the top when said top is removed from the bottle. This I consider a very important feature of my invention.

70 From the above described construction of parts, it will be seen that I have produced a very simple, strong and efficient bottle top which may readily be engaged with or disengaged from the neck of a bottle by hand, 75 without the use of any instruments whatever.

What I claim as my invention is:—

1. A device of the character described comprising; a cap formed of a single piece 80 of sheet metal and having a packing receiving socket and an annular inturned flange, a packing disk seated within said socket, and spring metal arms underlying said packing disk and having their ends 85 seated above said flange.

2. A device of the character described comprising; a cap formed of a single piece of sheet metal and having a packing receiving socket and an annular inturned flange, 90 a packing disk loosely seated within said socket, and a resilient polygonal retaining frame underlying said disk and having its corners resting on said flange.

3. A device of the character described 95 comprising; a cap formed of a single piece of sheet metal and having a packing receiving socket and an annular bead substantially U-shaped in cross section, a packing disk seated loosely within said socket, and a resilient rectangular frame underlying said disk and having its corners seated within said U-shaped bead.

4. A device of the class described comprising a cap member, the lower edges of 105 the side flanges of which are bent outwardly and thence inwardly to provide a channel-shaped bead, a packing disk arranged in said cap member, and a substantially rectangular clip formed of a single strand of 110

wire and arranged in the cap member to permit the corners thereof to be received in the channel-shaped bead, said clip retaining the packing disk in place when the cap member is in disuse and adapted for engagement with the bead of a bottle neck in the application of the cap thereto.

Copies of this patent may be obtained for five cents each, by addressing the "Commissioner of Patents, Washington, D. C."

In testimony whereof I have hereunto set my hand in presence of two subscribing witnesses.

OSCAR ROELKE.
